[57] CLAIM

The ornamental design for a brush baler cart, as shown and described.

DESCRIPTION

FIG. 1 is a left rear perspective view of a brush baler cart, showing my new design, the hinged compressor panel being shown in upright position;
FIG. 2 is an elevational view of one side, the opposite side being a mirror image thereof;
FIG. 3 is a front elevational view;
FIG. 4 is a rear elevational view;
FIG. 5 is a rear elevational view with the hinged compressor panel shown in horizontal position;
FIG. 6 is a bottom plan view; and,
FIG. 7 is a top plan view.
